UNITED STATES PATENT OFFICE.

JOSEPH KOWALSKI, OF SCHENECTADY, NEW YORK.

DESIGN FOR A CUSPIDOR.

41,788.

Specification for Design. Patented Sept. 19, 1911.

Application filed April 25, 1911. Serial No. 623,325. Term of patent 14 years.

To all whom it may concern:

Be it known that I, JOSEPH KOWALSKI, a subject of the Czar of Russia, residing at Schenectady, in the county of Schenectady and State of New York, have invented a certain new, original, and ornamental Design for a Cuspidor, of which the following is the specification, reference being had to the accompanying drawing, forming a part thereof.

The figure is a perspective view of the cuspidor, illustrating my new design.

I claim:—

The ornamental design for a cuspidor, as shown.

JOSEPH KOWALSKI.

Witnesses:

EDWIN SCHERMERHORN,
FRANK H. DETTBARN.
